AUTOMOBILE FLOOR MAT

James R. Caldwell, Wooster, Ohio, assignor to Wooster Rubber Company, Wooster, Ohio

Application September 24, 1954, Serial No. 32,420

Term of patent 14 years

(Cl. D9—6)

To all whom it may concern:

Be it known that I, James R. Caldwell, a citizen of the United States, residing at Wooster, in the county of Wayne and State of Ohio, have invented a new, original, and ornamental Design for an Automobile Floor Mat, of which the following is a specification, reference being had to the accompanying drawing, forming a part hereof, wherein:

I claim:

The ornamental design for an automobile floor mat, substantially as shown.
